UNITED STATES PATENT OFFICE.

ELMER E. HICKEN, OF COLLINGSWOOD, NEW JERSEY.

LOCOMOTIVE TENDER TANK.

Application filed March 21, 1927. Serial No. 177,151.

One object of this invention is to prevent the water striking hammer blows against the sides and ends of the tender tank, which are usually caused by the swashing of the water in the tank when the same is in motion.

A still further object of the invention is to make the tender tank rectangular in cross-section, which will increase the capacity of the tank and have the advantage of a cylindrical tank, where the capacity is limited.

By my invention I am enabled to increase the capacity of a tender tank, and at the same time prevent the water, when it swashes from side to side, striking hammer blows on the sides of the tank.

In the accompanying drawings:

Fig. 1 is a plan view, partly in section, of my improved tender tank;

Fig. 2 is a longitudinal sectional view;

Fig. 3 is a transverse sectional view on the line 3—3, Fig. 2;

Fig. 4 is a longitudinal plan view of one end of the tender; and

Figs. 5 and 6 are views illustrating modifications of the invention.

1 is the bottom of the tender tank; 2—2 are the side walls; 3 is the top; 4 is the rear end plate; 5—5 are transverse braces extending from side to side of the tank; and 6—6^a are vertical plates which act as braces and at the same time prevent longitudinal swashing of the water. In order to reinforce the bottom and top plates, transverse T-bars 16—16^a are arranged at intervals throughout the length of the tank and secured to said top and bottom plates. A central longitudinal plate extends from end to end of the tank.

At the two lower longitudinal corners of the tank are deflecting plates 7—7, which act to deflect the water as it swashes laterally, preventing the water striking hammer blows against the sides of the tank. These plates 7 are made in sections as shown in Figs. 2, 3 and 4, and the sections are located between the vertical plates 6 which extend from top to bottom of the tank. V-shaped openings 8 are formed at the lower corners of the sections to allow the plates to clear the transverse braces 16 and to allow water to circulate in the space back of the deflecting plates 7, and the plates 7 are discontinued at each end for the same purpose. The plates 7 prevent swashing of the water but do not decrease the capacity of the tank.

At the two upper longitudinal corners of the tank are deflecting plates 9—9 which deflect the water at the upper end of the tank when the tank is full. These deflecting plates also act as stiffening members for the corners of the tank.

At the rear end of the tank are upper and lower inclined deflecting plates 10 and 11, which prevent hammer blows at the end of the tank.

The general construction of the tank may be modified from the construction illustrated without departing from my invention. In this tank there is the usual space 12 for coal at the forward end of the tank. The longitudinal reflecting plates stop on a line with the coal space as shown in Fig. 1, and a vertical brace plate 13 acts as a swash plate at this point, as well as a support for the inclined back plate 14 of the coal space 12.

In the modification shown in Fig. 5, the deflecting plates 7^a—9^a extend from a point near the rear end of the tank to a point in line with the coal section, while the vertical plates 6^b extend only from a lower plate 7^a to an upper deflecting plate 9^a, being secured to said plate by angle bars.

In the modification illustrated in Fig. 6, curved plates 7^b—7^b are shown in place of the angular plate illustrated in Fig. 3, and I have also shown in this figure the upper portion of the tank rounded, as at 15, to produce a deflector. This, however, decreases the capacity of the upper portion of the tank.

While my invention is particularly adapted for use as a locomotive tender tank, it also can be used for the tanks of oil and other tank cars or trucks, where it is desired to increase the capacity and yet prevent the swashing of the liquid within the tank.

I claim:

1. The combination in a tank having its lower portion rectangular in cross-section, of longitudinal deflecting plates at the lower corners of the tank and arranged at an angle in respect to the sides of the tank, said plates being so arranged that water can gain access to the space back of the plates, said plates preventing the water striking direct blows against the sides of the tank.

2. The combination in a tank in which the sides are at right angles to the bottom thereof, of a longitudinally deflecting plate arranged at an angle at each side of the tank near the bottom; and longitudinally de-

flecting plates arranged at an angle at each side of the tank near the top of the tank so as to deflect the water as it is swashed due to the motion of the tank.

5. 3. The combination in a tender tank having its lower portion rectangular in cross-section, of longitudinally deflecting plates at the two lower corners of the tank and spaced from each end thereof; so as to allow water 10 to gain access to the space back of the plates.

4. The combination in a tender tank having its lower portion rectangular in cross-section, of longitudinal deflector plates arranged at an angle at the lower corners of 15 the tank; and vertical plates spaced apart and acting as braces as well as means for preventing longitudinal swashing of the water in the tank.

5. The combination in a tender tank rectangular in cross-section, of angularly deflecting plates located at the four corners of the tank and spaced from each end thereof so as to allow water to gain access back of the plates; vertical plates arranged at intervals throughout the length of the tank; and transverse braces extending from side to side of the tank and secured to the vertical plates.

6. The combination in a tender tank having its lower portion rectangular in cross-section, of vertical plates spaced apart and extending from top to bottom of the tank;

and longitudinal deflecting plates arranged at an angle at each side of the tank near the bottom thereof, said deflecting plates being 35 made in sections, each section being located between two vertical plates and secured to said vertical plates.

7. The combination in a tender tank having its lower portion rectangular in cross-section, of a bottom plate; transverse braces therefor; side plates and vertical plates arranged at intervals and secured to the braces; and longitudinal deflecting plates arranged at an angle at each side of the tank and near 40 the bottom thereof, said plates being shaped at the lower edge to clear the transverse braces and to allow for the circulation of water back of the plates.

8. The combination in a tank having its lower portion rectangular in cross-section, of longitudinal end plates at the lower corners of the tank and arranged at an angle in respect to the sides of the tank; and transverse inclined deflecting plates at the rear 50 end of the tank.

9. The combination in a tank rectangular in cross-section, of upper and lower longitudinally deflecting plates arranged at an angle in respect to the sides of the tank; and upper and lower inclined deflecting plates at the rear end of the tank.

ELMER E. HICKEN.
